(57) **CLAIM**

The ornamental design for a door panel grouping, as shown and described.

DESCRIPTION

FIG. 1 is a perspective view of a plurality of raised door panels of the present invention. The broken lines are for purposes of showing the environment of a door, which form no part of the claimed design.

FIG. 2 is a front view of the plurality of raised door panels shown in FIG. 1. The broken lines are for purposes of showing the environment of a door, which form no part of the claimed design; and,

FIG. 3 is a cross-sectional view of the raised door panels of the present invention along line 3 shown in FIGS. 1 and 2.
